UNITED STATES PATENT OFFICE.

JOHN P. SYKES, OF WALLINGFORD, AND SAMUEL R. LIMERICK, OF PHILADELPHIA, PENNSYLVANIA, ASSIGNORS TO THE BALDWIN LOCOMOTIVE WORKS, OF PHILADELPHIA, PENNSYLVANIA, A CORPORATION OF PENNSYLVANIA.

JIG FOR ASSEMBLING LOCOMOTIVE FRAMES.

1,425,296.

Specification of Letters Patent. Patented Aug. 8, 1922.

Application filed June 9, 1921. Serial No. 476,183.

To all whom it may concern:

Be it known that we, JOHN P. SYKES and SAMUEL R. LIMERICK, citizens of the United States, residing, respectively, in Wallingford, Delaware County, Pennsylvania, and Philadelphia, Pennsylvania, have invented certain Improvements in Jigs for Assembling Locomotive Frames, of which the following is a specification.

10 Our invention relates to certain improvements in jigs for assembling the side frames of a locomotive, or the frames of other structures, so as to insure the proper alignment of one frame with respect to the other, and 15 the correct assembling of the several elements, which are secured to the side frames.

The object of our invention is to simplify the construction of jigs of this type so as to make the parts readily adjustable and to provide means whereby the assembled frames 20 can be shifted to one side and removed bodily from the jig.

In the accompanying drawings:

25 Fig. 1 is a perspective view showing the two side frames of a locomotive on the assembling jig;

Fig. 2 is a transverse sectional view showing the frames on the jig;

30 Fig. 3 is a sectional view, similar to Fig. 2, showing the frames shifted to one side and the assembled structure suspended from a crane;

Fig. 4 is a perspective view of one of the 35 saddles; and

Fig. 5 is a perspective view of one of the intermediate supporting struts.

Referring to the drawings, 1 is the base 40 having two parallel channels 3. 2 are the saddles mounted on the base and having 45 tongues 4 adapted to the channels 3 of the base, so that they can be shifted to any position desired on the base and held by bolts 5, or other fastenings. Each saddle has two uprights 6, 6^a, suitably braced, and on each 50 upright is a cross head 7. On the cross head of the upright 6 are two projections 8 and 9. The projection 8 is considerably higher than the projection 9. On the cross head of the upright 6^a are two projections 8^a and 9^a spaced a greater distance apart than the 55 projections 8 and 9.

The frames *a*—*a* of the locomotive may be of different shapes. In the present instance, each frame *a* has four pedestal open-

ings *b*. The cross heads 7 extend through 55 two of these openings on each side, as clearly shown in Fig. 1. In assembling the structure, one frame is mounted on the cross heads of the two uprights 6, at one side of the jig and secured thereto by clamps 11, or other suitable fastenings, Fig. 2. Then the other frame is located on the cross heads of the uprights 6^a at the other side of the jig. Spacers *c* are used to locate the frames a given distance apart. These spacers, in the 65 present instance, are notched so as to fit over the frames.

The permanent cross frames *d* are located in position and securely bolted to the side frames, and cylinder saddles *e* may be secured in position and other parts may be located and secured in position, as desired. When it is necessary to support the frames midway between the saddles, a supporting 75 strut 10, as shown in Fig. 5, may be located at any convenient point and bolted to the base and to one of the side frames in order to hold the frames rigidly in position.

In Fig. 1 of the drawings, the clamping 80 means for temporarily securing the frames to the saddles of the jig are not shown.

After the frames have been assembled on the jig, the clamps can be removed and suitable chains can be attached so as to be connected to a hoisting apparatus and the entire 85 structure, consisting of the two side frames of a locomotive and the assembled parts, can be raised off of the saddles and moved laterally, as shown in Fig. 3, and then raised 90 clear of the jig and shifted to any point desired.

By the above construction, the frames can be readily assembled and can be trued, one in respect to the other, insuring perfect alignment. The structure, when completely 95 assembled, can be easily and quickly removed from the jig, as a unit.

We claim:

1. The combination in a jig, of a base; 100 saddles mounted on the base, each saddle having two uprights spaced apart, the uprights on one side being arranged to support one side frame of a locomotive, and the uprights on the other side being arranged to support the other side frame of a locomotive 105 and when the two frames are connected together they can be bodily removed from the uprights by a lateral movement.

2. The combination in a jig for assembling locomotive and other frames, of a base; two saddles adjustably mounted on the base, each saddle having two uprights spaced apart; a cross head on each upright, one of said cross heads having projections so that the frame can be mounted on the cross heads and secured against the projections, the other cross head being adapted to receive another frame; and spacing members for spacing the frames a given distance apart, the saddles being so constructed that, when the frames are connected together, the structure can be removed bodily from the jig by first moving the structure laterally and then elevating it clear of the jig.

3. The combination in a jig for assembling locomotive and like frames, of two saddles, each saddle having two uprights spaced apart; and a crosshead on each upright, each cross head having projections to accommodate the frames to be assembled when mounted on the cross heads.

4. The combination in a jig for assembling locomotive and like frames, of a base having two longitudinal slots therein; two saddles having tongues adapted to the slots; means for holding the saddles in the position to which they are adjusted; and an

intermediate supporting strut adjustably mounted on the base, each saddle having two cross heads spaced apart to receive the two side frames of a locomotive, the supporting strut being arranged to be secured to one of said side frames to support it between the saddles.

5. The combination in a jig for assembling locomotive frames, of a base; and two saddles mounted on said base, one saddle being adjustable on the base in respect to the other, each saddle having means for supporting the frames of a locomotive.

6. The combination in a jig for assembling locomotive frames, of a base; and two saddles mounted on said base and adjustable thereon, said saddles having means for supporting the side frames of a locomotive.

7. The combination in a jig for assembling locomotive frames, of a base having longitudinal guides; saddles mounted on the base and adapted to the guides; and means securing the saddles in the position in which they are adjusted, said saddles having means for supporting the side frames of a locomotive.

JOHN P. SYKES.

SAMUEL R. LIMERICK.
